SAFE.

No. 594,378.

Patented Nov. 30, 1897.

UNITED STATES PATENT OFFICE.

THOMAS M. BRINTNALL, OF MEDINA, OHIO, ASSIGNOR TO THE NATIONAL
SAFE AND LOCK COMPANY, OF CLEVELAND, OHIO.

SAFE.

SPECIFICATION forming part of Letters Patent No. 594,378, dated November 30, 1897.

Application filed June 1, 1893. Serial No. 476,307. (No model.)

To all whom it may concern:

Be it known that I, THOMAS M. BRINTNALL, a citizen of the United States, and a resident of Medina, county of Medina, State of Ohio, 5 have invented certain new and useful Improvements in Burglar-Proof Safes, of which the following, with the accompanying drawings, is a specification.

My invention relates to what are known as 10 "circular-door" safes; and its object is to provide said safes with an improved form of screw locking device, and also to provide such safes with an improved bolt-locking device which automatically locks the safe upon turning the safe-door through a partial revolution, and to the combination of both my improved 15 screw and automatically-operated bolt-lock to give a more secure fastening to the safe-door.

20 My invention consists in the construction and combination of parts illustrated in the drawings, described herein, and defined in the claims.

In the drawings, Figure 1 is a front elevation of a safe with my improvements. Fig. 25 2 is a central vertical section of Fig. 1. Fig. 3 is a view of the back of the door from the inside of the safe, a part of the cap which closes my automatic bolt-lock being broken 30 away. Fig. 4 is an elevation of the back of my safe-door complete. Fig. 5 is an enlarged section which illustrates the vertical and horizontal adjustment of the ring which is carried by the crane-hinge and supports the safe-door. Fig. 6 is an enlarged detail of the pinion and segmental gear which are employed 35 to turn the safe-door, and Fig. 7 is an enlarged broken section illustrating the arrangement of the puppet for holding the lock-bolts out 40 of engagement with their sockets and the means for releasing said puppet to allow the bolts to be automatically thrown.

In the drawings the safe is represented as closed and locked.

45 The safe-body 1 is of the ordinary construction and has a circular front opening which is closed by a circular door, as hereinafter described.

Within the circular front opening of the

safe-body 1 upon the inner side of the safe is 50 fixed a ring 2, having the mutilated female screw 3. A swinging crane-hinge 4 is secured to the front of the safe by means of the bolts 5 and 5', which pass through the brackets 6 and 6', upon which bolts 5 and 5' the crane-hinge 4 swings. A ring 7 is carried by the crane-hinge 4 and has vertical and horizontal adjustment with reference to the crane-hinge 4. The vertical adjustment of the ring 7 with 55 reference to the crane-hinge 4 is secured by 60 means of the screw-bolts 8 and 8' and the nuts 9 and 9'. To secure horizontal adjustment of the ring 7 with reference to the crane-hinge 4, I form sockets 4' in the ends of the crane-hinges 4, as illustrated by Fig. 5, and insert 65 therein blocks 10, through which pass the vertical bolts 8 and 8'. Said blocks 10 are given adjustment horizontally by means of the screws 11 and 11'.

Upon the front face of the door 12 is fixed 70 a ring 13. The ring 13 is grooved on its outer face and the ring 7 is grooved upon its inner face. The ring 13 fits within the ring 7, and the two grooves form a circular way 14, which have ball-bearings 15, as seen by the dotted 75 lines in Fig. 1, for the purpose of more easily turning the safe-door. Upon the front of the ring 13 is fixed a circular plate 16, upon the upper side of which is fixed a segmental gear 17. This plate 16 closes the opening of the 80 ring 13 to give the safe a neater appearance. The ring 13 may be as well a solid plate, but such construction would add to the weight 85 and expense of the door without any corresponding advantages.

Upon the ring 7 is pivoted a pinion 18, which meshes with the segmental gear 17, and a gear 19 is pivoted upon the ring 7 to mesh with the pinion 18, and a crank 19' serves to turn the pinion 19. The pinion 19 turns upon 90 a post 20, which projects through the cap 21, that closes over the segmental gear 17 and pinions 18 and 19 to give the safe a neater appearance and to protect said pinions and gear from dust collection. The crank 19' fits 95 upon the outer end of the post 20. It will be seen that by turning the crank 19' the door 12 will be rotated independently of the ring

7. The employment of the two pinions 18 and 19, instead of the employment of a single pinion to mesh with the segmental gear 17, that is attached indirectly to the door 12, 5 causes the door to rotate in the same direction that the crank 19' is turned. This is done for convenience and to avoid confusion in rotating the safe-door. It will be seen that the safe-door 12, with the ring 7, has a 10 limited movement upon the pins or screw-bolts 8 and 8', so that as the crane 4 is brought around to close the door the door will turn by means of said pivots 8 and 8' to let it swing straight into position in the circular front 15 opening of the safe-body.

Upon the inner face of the door 12 is a plate 22, provided with a ring 23, which ring 23 forms a mutilated male screw which enters and interlocks with the female screw formed 20 by the ring 2 upon a partial revolution of the door 12. A plate 24 is secured to the mutilated male screw-ring 23 by means of the bolts 25. A pin 26 passes through the plate 24 and extends into the chamber formed between the plates 24 and 22. A plate 27, within the ring 23, is journaled upon the pin 26 and is provided with segmental grooves 27'. Bolts 28, having studs 28' formed thereon, pass through lateral openings in the male 30 mutilated screw-ring 23 and are adapted to engage sockets formed in the female screw-ring 2. The studs 28' travel in the segmental grooves 27'.

Upon the plate 22 are fixed guides 29 for 35 the bolts 28, which guides have vertical slots 29' to allow the bolts to travel out and in. Around the pin 26 is coiled a spring 30, having the two ends 30' and 30" secured to the segmental grooved plate 27. In the plate 27 is 40 formed a puppet-hole 31. Upon the outer side of the plate 24 is fixed a bracket or shell 32, through which passes a puppet 33, having a head 33' and a ring 33" shrunk upon the puppet within the casing 32. A spring 34 is 45 interposed between the top of the casing 32 and the ring 33". A throw 35 is pivoted to the plate 24 at 35'.

To the female screw-ring 2 is secured a trip 36, which trip 36 is adapted to let the outer 50 end of the throw 35 pass under it and throw out the puppet 33 to the position illustrated by the drawings when the safe is locked.

In the plate 24 is formed a segmental slot 55 37, through which passes a pin 38, that is attached to the segmentally-grooved plate 27. By means of the pin 38 the plate 27 may be turned through an arc of a circle of the length of the slot 37. A dog 39 is pivoted to the plate 24 at 40 and has a shoulder 39', which is 60 adapted to engage the pin 38. A link 41 is pivoted to the plate 24 above the free end of the dog 39 and has a lug 41' formed thereon, which lug is adapted to engage the free end of the dog 39.

42 represents the outline of a time-lock, 65 which is secured to the plate 24.

Having fully described the construction of my improvements, I will now describe their operation. First, I will describe the manner in which the safe is opened, for the reason 70 that it is illustrated as being closed and locked. At the time set the time-lock 42 swings the link 41, as indicated by the dotted lines in Fig. 4, so that the outer end of the dog 39 is raised and the pin 38 is released 75 from the shoulder 39'. The spring 30 then throws around the plate 27, and the travel of the lugs 28' in the segmental grooves 27' withdraws the bolts 28 from the sockets in the female ring 2 in which they were engaged. The 80 pin 38 will strike against the left end of the slot 37 and prevent the plate 27 from turning beyond a fixed point. It will be seen that upon the release of the dog 39 by the time-lock 42 my device automatically unlocks the 85 bolts 28. By turning the crank 19' to the left the door is turned through a portion of a revolution, and the mutilated male screw becomes unlocked from the mutilated female screw, when the door may be swung open upon the 90 crane-hinge 4. When it is desired to close the safe and lock it, the pin 38 is thrown to the right end of the slot 37, thereby swinging the plate 27 around, so that the puppet 33 will enter the hole 31 and hold the plate 27 rigid with the 95 bolts 28 withdrawn to their extreme back stroke. The safe-door is then swung into place in the circular front opening of the safe and is turned to the right by means of the crank 19'. As the crank is turned the male 100 mutilated screw interlocks with the female mutilated screw and the outer end of the throw 35 engages the trip 36, withdraws the puppet 33 from the hole 31, thus releasing the plate 27 and allowing the spring 30 to operate 105 to turn the plate 27 and throw the bolts 28 into the sockets formed in the female mutilated ring 2. It will be seen that by turning the safe-door to lock it with the male and female screws it automatically locks by means 110 of the bolts. When the pin 38 is swung to the right end of the slot 37, so that the puppet 33 enters the hole 31, the dog 39 drops by gravity, so that the shoulder 39' engages the pin 38 as the plate 27 turns back upon the 115 release of the puppet 33 from the hole 31.

It will readily be seen that my improvement furnishes a form of screw-lock which is very effective and requires a shorter turn of the safe-door than the screw-doors heretofore 120 in use, and it also provides circular safes with improved bolt-locks, which automatically lock the safe upon turning the safe-door through a partial revolution, and that the combination of two locks in one safe makes 125 the door very secure.

While I do not broadly claim a circular screw-bind door for safes, I do not limit my-

self to the exact form of construction of parts as illustrated and described, for my improvement may take on various mechanical details of construction without departing from the 5 spirit of my invention.

What I claim as my invention, and desire to secure by Letters Patent, is—

1. The combination of a safe-body having a circular front opening and a mutilated female screw, a swinging crane-hinge provided with a ring having vertical and horizontal adjustments, a circular door also provided with a ring and supported by said hinge, a mutilated male screw located on the door and adapted to 10 enter and interlock with the female screw in the door-frame, and retaining means which automatically enter sockets when the safe-door shall have been turned a partial revolution to lock the safe, substantially as described.

2. The combination of a safe-body having a circular front opening and a mutilated female screw, a swinging crane-hinge secured to the front of the safe-body, a ring carried by 25 the crane-hinge and having vertical and horizontal adjustments thereon, a circular door provided with toothed gearing, an intermediate pinion carried by the ring and gearing with the toothed gearing on the door, a driving-pinion also located on the hinge-ring and 30 gearing with the first-mentioned pinion but not meshing with the toothed gearing on the door, whereby the door may be given a rotary motion in the direction of the crank 35 through the arc of a circle, and a mutilated male screw secured to or formed upon the door, said male screw being adapted to enter and interlock with the female screw upon a partial revolution of the door, substantially 40 as described.

3. The combination of a safe-body having a circular front opening and a mutilated female screw, a swinging crane-hinge secured to the front of the safe-body, a ring carried 45 by said crane-hinge and having vertical and horizontal adjustment thereon, a circular door carried by said ring, a segmental gear secured to the door and a pinion secured to said ring, means for turning said pinion whereby the 50 circular door is turned through the arc of a circle, a male screw upon the door, the male screw being adapted to enter and interlock with the female screw, and bolts which automatically engage sockets as the door is turned 55 to lock the safe, substantially as illustrated and described.

4. The combination in a safe, of a circular door provided with a ring having gear-teeth, a crane-hinge carrying a ring, a driving-pinion on said hinge-ring, a driven pinion also 60 on said hinge-ring and interposed between the driving-pinion and the gear-teeth on the door and meshing with said driving-pinion and toothed gearing, whereby in opening and closing the door it will be turned in the same

direction as the crank-operating handle is turned, substantially as described.

5. The combination of a ring, a safe-door having upon its face a ring which fits into the first-mentioned ring, ball-bearings between 70 said rings, a toothed gear provided in the ring that is attached to the safe-door, a driven pinion mounted on the first-mentioned ring and meshing with a driving-pinion, the said driven pinion meshing with the toothed gear 75 ing on the door, the door also provided with a female mutilated screw which interlocks with a mutilated male screw on the door-frame, substantially as described.

6. In a safe, an automatically-operating 80 bolt-lock consisting of a plate having formed in one of its faces segmental grooves, bolts provided with studs which travel in said segmental grooves, and a spring which automatically rotates said plate through the segment 85 of a circle and throws the bolts, substantially as illustrated and described.

7. A circular safe-door having secured to its inner face an annular ring, lateral openings through the ring, a plate within the ring, 90 said plate having segmental grooves formed in one of its faces, bolts which pass through the lateral openings of the ring and have studs which travel in said segmental grooves, and means for automatically rotating said plate 95 independently of the door and automatically throwing said bolts, substantially as illustrated and described.

8. A circular safe-door, a ring secured to the inner face of the door, lateral openings 100 through the ring, a circular plate within the ring, said plate having segmental grooves formed in one of its faces, bolts which pass through the lateral openings of the ring and are provided with studs which travel in said 105 segmental grooves, a spring to rotate said plate independently of the door, a puppet adapted to hold said plate in a fixed position when the bolts are withdrawn from the sockets of the safe-body, and means for automatically 110 releasing said puppet when the safe-door is partially revolved, whereby the plate is caused to rotate independently of the door and automatically throw the bolts, substantially as 115 illustrated and described.

9. The combination with a safe-body, of a door, a crane-hinge having supporting-arms provided with vertical and horizontal adjusting-screws for adjusting the hinge and door supported thereby in a vertical and horizontal direction, whereby the door can be perfectly adjusted with respect to the door-frame and be held in such adjusted position, substantially as described.

10. In a safe, the combination with an automatic bolt-locking mechanism, of a pin connected with and operated by said automatic bolt-locking mechanism, a pivoted time-lock-tripping lever provided on its lower end with a segmental retaining-rim, a dog-lever piv- 125 130

oted at or near one of its ends and provided between its pivot-point and toe-engaging end with a heel-stop for retaining the pin connected with the automatic bolt-locking mechanism in position, the length of the dog-lever from its pivot to its toe-engaging end being equal to the distance from the center of its pivot to the center of the pivot of the time-lock-tripping lever, whereby all strain on the time locking mechanism is obviated, and a

positive lock of the time locking-trip secured, substantially as described.

In testimony whereof I affix my signature, in the presence of two witnesses, this 26th day of May, 1893.

THOMAS M. BRINTNALL.
